STACK DESIGN

Ward B. Traver, Hammond, Ind., assignor to Standard Oil Company, Chicago, Ill., a corporation of Indiana

Application December 28, 1949, Serial No. 135,481

3 Claims. (Cl. 98—60)

1

This invention relates to an improved stack design and it pertains more particularly to an improvement in the design of tall, cylindrical stacks, such as steel stacks which, in the absence of said improvement, would have a tendency toward lateral vibration at a particular wind velocity.

An object of the invention is to provide a cylindrical stack which will avoid the necessity of using guy wires or expensive stiffening structure when said stack is of such height and diameter that its natural frequency of lateral vibration is in the range of about 1 to 3 cycles per second. A further object is to provide a method and means for stabilizing existing stacks against lateral vibration. Other objects will be apparent as the detailed description of the invention proceeds.

Stacks which are of conical section from top to bottom present no lateral vibration problem and this invention is directed to cylindrical stacks and to stacks having a tall, cylindrical portion mounted on a conical base. The invention is particularly applicable to stacks of about 2 to 15 feet or more in diameter and with a cylindrical section height of the order of 50 to 200 feet or more. Each such stack has its particular natural frequency of lateral vibration which can readily be calculated by those skilled in the art. When such natural frequency of vibration is in the range of about 1 to 3 cycles per second, particularly in the case of stacks which are upwards of about 100 feet in height, it has long been known that there is a tendency for the stack to vibrate laterally at a determinable wind velocity. Heretofore it has been the practice to employ guy wires to prevent such lateral vibration or to provide stiffening structure required for altering the natural frequency of the stack.

I have discovered that such stacks can be protected against lateral vibrations by affixing protuberances on at least the upper portion of the stack, the protuberances being of sufficient height and of such geometric arrangement as to interfere with regularly alternating formation of vortices on opposite sides of the stack. The required height and geometric arrangement of the protuberances will depend to some extent on the diameter of the stack but the height must be at least substantially equal to the depth of the retarded layer of the moving air stream near the stack surface, and the geometric arrangement must be such as to break up this surface air stream layer and create turbulence in order to avoid or minimize regular vortex formation. For

most stacks the protuberances should be from about one-fourth inch to one inch or more in height and they are preferably in the form of staggered short strips of light metal spaced circumferentially at about 10 to 15 degree intervals or at distances from one-half foot to two feet apart. Close spacing of the protuberances is more effective than the use of wider spacing but higher protuberances. The protuberances may be formed of vertical angle bars of light metal and such angle bars may provide increased stiffening and re-enforcement, but for my purpose such structural strength is immaterial and staggered protuberances are even more effective than angle bars. The protuberances may be in the form of woven wire or expanded metal around the upper portion of the stack provided that such material is of sufficient thickness to obtain the required disturbances of air flow at the surface of the stack.

The invention will be more clearly understood from the following description of a specific example, read in conjunction with the accompanying drawings which form a part of this specification and in which:

Figure 1 is a diagrammatic view of a steel stack mounted on a conical base;

Figure 2 is a plan view of the upper part of stack showing radial protuberances;

Figure 3 is a plan view of the upper part of stack showing tangential protuberances;

Figure 4 is a plan view of the upper part of stack showing protuberances of circular cross section area; and

Figure 5 is a detail illustrating the use of a fabric mesh protuberance arrangement.

In this particular example, the stack consists of a cylindrical portion 10, which is 4 feet 3 inches in diameter and 95 feet high mounted on a frusto-conical steel base 11, 30 feet high and 7 feet in diameter at its base. In this case the stack wall thickness is about $\frac{1}{8}$ inch. The stack base in this case is bolted to concrete foundation and the natural frequency of lateral vibration for this particular stack is shown by calculation to be about 1.6 cycles per second.

If such a stack were not re-enforced by guy wires or stiffened by expensive re-enforcing means, it would be subject to such intensive lateral vibration at a wind velocity of about 24 miles per hour as to be in danger of rupture or collapse. At low wind velocities of the order of one mile per hour, the vortices on each side down-stream would be relatively equal and of no serious effect. At higher wind velocities there

will be an alternating formation of vortices first on one side and then on the other, the effect of which is to subject the stack to lateral forces transverse to the wind direction, which forces are exerted alternately on each side of the stack. The frequency of alternate vortex formation is substantially as shown by the formula

$$F = .28 \frac{V}{D}$$

where F is the vortex frequency in cycles per second, V is the wind velocity in miles per hour and D is the stack diameter in feet. This alternate vortex formation has no serious effect toward causing stack vibration until said frequency substantially equals the natural frequency of the stack in lateral vibration. In this particular example, when the wind velocity reaches 24 miles per hour, the frequency of vortex formation will be in resonance with the stack's natural frequency of lateral vibration and the net result will be a gradual increase in amplitude of vibration which may become so severe as to cause failure of the stack. If the wind velocity exceeds 24 miles per hour, the frequency of vortex formation will no longer be in resonance with the stack's natural frequency and at wind velocities sufficiently high to result in turbulent flow, there is no longer a vibration problem.

Referring again to the drawing, it will be noted that the upper half of the stack is provided with protuberances 12 which in this particular example are thin metal strips about 6 inches long and $\frac{3}{4}$ inch wide. These strips are spot welded, brazed or otherwise secured to the stack so that they are each in a vertical position but are spaced from each other by about one foot and are staggered or geometrically arranged so as to give maximum disturbance to the surface layer of air which is flowing past the stack. With such protuberances, which in this case are $\frac{3}{4}$ inch high, relatively closely spaced and geometrically arranged to disturb surface flow, the tendency toward vortex formation is markedly altered. With such protuberances on the upper part of the stack, turbulent flow conditions are obtained with a wind velocity so low that the frequency of vortex formation cannot attain the stack's natural frequency of vibration so that there is no longer any tendency for the stack to vibrate at the wind velocity of 24 miles per hour or in fact at any other wind velocity. In other words, by roughening the surface of at least the upper part of the stack in the defined manner, I lower the maximum possible frequency of vortex formation to such extent that it is less than the stack's natural frequency of lateral vibration.

I have solved the vibration problem by altering fluid flow past the stack surface instead of by altering the stiffness of the stack itself or securing the stack against vibration by means of guy wires.

In the above specific example, I employ geometrically spaced metal strips for distributing the surface flow of air past the stack but it should be understood that the disturbance of surface flow may be effected by various other types of protuberances. Such protuberances may be along the entire cylindrical portion of the stack but usually it is only necessary that the upper half or upper one-third of the stack be provided with protuberances because of the higher wind velocities and the greater effectiveness of the force exerted on the stack's upper end. The vertical strips may extend from top to bottom

at spaced intervals of about 10 to 45 degrees around the stack, the protuberances may be either radial 13 as shown in Fig. 2, or tangential 14 as shown in Fig. 3. They may be rectangular in cross section or circular in cross section as exemplified by the cylindrical protuberances 15 in Fig. 4. The protuberances may be in the form of a woven wire fencing or expanded metal lath fabric 16 as illustrated in Fig. 5. Such woven wire fencing or expanded metal lath is not as effective as the strip protuberances which extend at least about one-quarter inch to an inch or more from the stack surface unless the expanded metal or woven wire extends outwardly far enough to disrupt the retarded surface-layer of the air stream flowing around the stack (in most cases at least about one-quarter inch).

The reason for having the protuberances at spaced intervals around the circumference of the stack is to protect the stack against lateral vibration regardless of wind direction. If a stack were in a location where the wind was always from the same direction then it would only be necessary to have protuberances on each side of the stack about 70° to 80° from the direction of the wind on the up-stream side. If strips or vanes were movably mounted and directed, for example, by a wind vane so that the strips would always be at about 70° to 80° from the direction of the wind on the up-stream side, the objects of my invention could be accomplished without employing the strips at spaced intervals around the entire stack. For practical purposes, however, it is usually desirable to employ fixed protuberances at sufficiently close intervals so that the retarded surface or boundary layer flow is necessarily disrupted regardless of wind direction. The boundary layer thickness of a flowing air stream is somewhat dependent on wind velocity, but at any particular velocity it increases in depth with increase in stack diameter. The minimum protuberance depth for a 2 foot diameter stack is approximately one-quarter inch, but protuberances of greater depth may be employed. The minimum protuberance depth for a ten foot diameter stack is about three-quarter inch. In all cases the protuberances may be two or three inches, but the use of higher protuberances may be objectionable because of increased drag.

I claim:

1. A cylindrical stack having a natural frequency of lateral vibration in the range of about 1 to 3 cycles per second and having protuberances on at least the upper portion of its external surface, said protuberances being at least about one-quarter inch to one inch in depth and being spaced laterally around the stack at intervals of about six inches to two feet whereby said protuberances disrupt the surface air stream flowing past the stack and interfere with regularly alternating formations of vortices on opposite sides of the stack.

2. The cylindrical stack of claim 1 wherein the protuberances consist of vertically aligned flat strips attached tangentially to the surface of the stack of sufficient width so that their free edges are about one inch from the surface of the stack, spaced laterally around the stack at intervals of about ten to forty-five degrees.

3. The cylindrical stack of claim 1 wherein the protuberances consist of a sleeve of wire fabric around the stack wherein the thickness of the fabric is not less than about one-quarter inch.
